C. W. LAKE,

ATTACHMENT FOR PUMPS.
APPLICATION FILED FEB. 9, 192

1,406,036.

Patented Feb. 7, 1922.

FIG. 1.

17 138 55 112
Charles H. Lake
By Frank P. Walton his Attorney

UNITED STATES PATENT OFFICE.

CHARLES W. LAKE, OF McPHERSON, KANSAS.

ATTACHMENT FOR PUMPS.

1,406,036.

Specification of Letters Patent.

Patented Feb. 7, 1922.

Application filed February 9, 1921. Serial No. 443,602.

To all whom it may concern:

Be it known that I, CHARLES W. LAKE, a citizen of the United States, residing at McPherson, in the county of McPherson 5 and State of Kansas, have invented a new and useful Attachment for Pumps, of which the following is a specification.

The present invention relates to means applied to the so-called purifying well 10 pumps, particularly the bucket type, the purpose of the invention being to increase the purifying action of the pumps.

The so-called purifying well pumps are so designated because of the agitating effect 15 they have upon the water in the well and further because of their construction. It is found however that wells which are not frequently used, the purifying pumps do not agitate and aerate the water sufficiently to 20 keep it pure and to expel the foul air within the well.

The present invention is an appliance either in the form of an attachment, to be applied to existing pumps or to be applied 25 to pumps in their manufacture, for permitting the water pumped or raised in the well to be turned back for the purpose of creating an air circulation in the upper portion of the well and for further agitating the 30 water, thus resulting in greater aeration of the water and in the expelling of foul air and gases which accumulate above the surface of the water.

With the above and further objects in 35 view the invention further resides in the sundry details of construction and in the combination and arrangement of parts hereinafter pointed out in detail.

In this specification and the annexed 40 drawings, the invention is disclosed in the form in which it is considered to be the best, but the invention is not limited to such form because it is capable of being embodied in other forms; and it is to be understood 45 that in and by the claims following the description herein it is intended to cover the invention in whatever form it may embody within the scope thereof.

In the drawing is illustrated one form of 50 pump to which the invention is applicable and in which,

Figure 1 illustrates the ordinary bucket pump in side elevation and the well in vertical section, the various parts in the pump 55 casing being indicated in dotted lines to

disclose the interior construction and arrangement;

Fig. 2 is an enlarged fragmentary detail view through the pump casing illustrating the manner in which the endless buckets 60 elevate and discharge the water from the well, the pump being equipped with the invention;

Fig. 3 is a view similar to Fig. 2 illustrating the invention moved to operative position and turning back the pumped or raised 65 water into the well, and

Fig. 4 is a top plan view of the pump shown in Fig. 1.

Referring particularly to the drawings 1 70 indicates a well, and 2 the usual form of endless bucket pump mounted on the top of the well. The bucket pump comprises a casing 3 having mounted near its upper portion a transverse shaft 4, having mounted 75 thereon and within the casing the usual sprocket wheel or pulley 5 over which passes an endless chain or cable 6 carrying thereon spaced buckets 7. The chain or cable 6 is of such length as to extend to the well below 80 the water level and, in some instances, a lower sprocket wheel or pulley 8 may be mounted below the water level in the well and over which pulley 8 the endless buckets 85 pass.

The shaft 4 is preferably provided with a gear 11 at its ends to mesh with a gear 12 on the usual crank handle 13 mounted exteriorly of the casing. It is also desirable in some instances to provide a pawl 14 which 90 may be moved into position to engage the gear 11 for permitting rotation of the wheel 5 in but one direction.

A funnel or pocket 9 is provided within 95 the casing, usually on the front wall thereof, in such relation with respect to the wheel or pulley 6, that the buckets 7 discharge thereinto as they pass over the wheel to descend into the well, as illustrated by the arrows in Fig. 2. The usual discharge spout 100 10 extends from the casing 3 of the pump and is in communication with the funnel 9. The above is the usual construction of bucket pumps and forms no part of the present invention except as may further appear by 105 reason of the combination and arrangement of elements.

The present invention consists of the member 15 in the form of a chute or trough provided with a bottom wall *a*, side walls 110

b, and end wall *c*, the other end of the trough or chute being opened as illustrated. The chute 15 is secured in any suitable manner at the lower portion of the end wall *c*, to a shaft 16. The chute 15 is of such size and formation as to be suspended from the shaft 16, the ends of which are journaled in the side walls of the casing 3, and lie over the entrance *x* of the funnel 9, the bottom wall *a* 10 of the chute normally lying against the front wall of the casing 3 as illustrated particularly in Fig. 2. In this position of the chute 15 it is apparent that the water raised by the bucket 7 will be discharged into the 15 funnel as usual, but, when the chute is moved to the position shown in Fig. 3, it will act as a valve for closing the entrance *x* of the funnel and divert the raised water back into the well. The chute 15 is, preferably, at least of the same width as the funnel 9 so that its bottom wall *a* will entirely obstruct the entrance opening of the funnel, said walls of the chute acting to prevent water from flowing around the sides of the 25 chute into the funnel.

By reason of the inclined position of the chute the water is quickly diverted back into the well in a steady stream which will cause a circulation of air in the pump and well above the water level in a manner understood. However, this downward stream of water will cause air circulation in the pump and aeration of the water in a manner well understood so as to relieve it of its 30 impurities. This aeration of water is also assisted by the normal operation of the endless buckets agitating the water.

The chute 15 is operated by means of a crank handle 17 on one end of the shaft 16, 40 the extremity of the handle being provided with a lateral finger or lug 18. To maintain the chute in the position shown in Fig. 3, for diverting the water back into the well, a trip arm 19 is pivotally mounted to the 45 casing in such relation with the handle 17 as to engage the handle and maintain it in the desired position.

It will be observed from Fig. 1 of the drawings that the chute operating handle 50 17 normally lies in a depending position and is moved upwardly to place the chute in operative position. With the chute so positioned the handle 17 assumes a substantially horizontal position.

55 The trip arm 19 is pivoted below the handle and is provided with a lateral offset portion to engage under the chute handle 17 to maintain it in its substantial horizontal position by reason of the offset portion 19^a of the trip engaging with the lug 18 of the chute handle. To release the chute from its operative position it is only necessary to slightly raise the handle 17 and move the trip arm to the position indicated in Fig. 1.

From the above it will be observed that a 65 very simple and economical attachment has been provided for the ordinary purifying pumps which will cause the water to be diverted back into the well for the purpose of expelling the foul air and gases and for injecting fresh air into the well for aerating the water. 70

In using the invention it is proposed that either after or before a supply of water has been obtained that the operator place the 75 chute in operative position, as shown in Fig. 3, and operate the pump for a desired period of time. Also the pump can be operated at leisure for the purpose of aerating the water and thereby always insure the freshness and 80 purity of the water.

I claim:

1. An attachment for well pumps equipped with a water-receiving chamber, means for delivering the water to the chamber and a 85 discharge leading from the chamber; said attachment comprising a shiftable member constructed to close said receiving chamber of the pump to the reception of water delivered thereto and to divert the water delivered to the chamber back into the well. 90

2. An attachment for pumps equipped with a water receiving chamber, means for delivering the water to the chamber, and a discharge leading from the chamber, said 95 attachment comprising a shiftable member constructed to close said receiving chamber of the pump and to divert the water delivered to the chamber back into the well, said member normally lying in inoperative position, and manually operable means for maintaining the member in operative position, whereby the water is diverted back into the well for purifying and aerating the water in the well. 100

3. In a pump, a water receiving chamber within the pump and having an open inlet, means for delivering water to the chamber, and means arranged over the inlet of said chamber and shiftable to a position to divert the water delivered to the chamber back into the well, a discharge spout for the pump, and a connection between said spout and said chamber. 105

4. In a pump, a funnel-like water receiving pocket, means for raising water in the pump and discharging it into the pocket, a trough-like member arranged over the funnel, said trough-like member being pivotally mounted and normally assuming an inoperative position, and being movable to close said pocket and to divert the water being delivered to the pocket back into the well, said pocket having a discharge outlet. 115

5. In a well pump, a casing, a discharge 120 spout projecting from the casing, a funnel-like water-receiving pocket secured to a wall of the casing and communicating with said

spout, means for raising water in the pump and discharging it into the pocket, a trough-like member pivotally mounted over said pocket and normally assuming an inoperative position, said trough-like member being movable to overlie the pocket and divert the water being delivered thereto back into the

well, and manually operable means for releasably retaining the trough-like member in operative position.

10

In testimony whereof I have hereunto set my hand.

CHARLES W. LAKE.
